UNITED STATES PATENT OFFICE

2,226,168

HANGER

Samuel M. Kass, Philadelphia, Pa.

Application August 9, 1939, Serial No. 289,212

3 Claims. (Cl. 248—217)

My present invention relates to a new article of commerce, a hardware novelty comprising a bracket or hanger for convenient attachment selectively either to a wall or to a ceiling.

5 A purpose of the invention is to provide a bracket of the character indicated selectively for two-nail or two-screw fastening to the ceiling or one-nail or one-screw fastening to a wall.

10 A further purpose is to form a bracket or hanger of the character indicated with a double hook contour, to present its one face (that of its inward and oppositely directed hooks) to a ceiling or its other face (with the hooks outward) to a wall according as it is applied to a ceiling 15 or to a wall.

15 A further purpose is to perforate spaced portions of a double hook bracket to receive outwardly toeing screws or nails if or when the bracket is to be applied as an eye to a ceiling or a downwardly toeing screw or nail if or when it is to be applied as a hook to a wall.

20 A further purpose is to oppositely recess the bracket at the middle thereof to accommodate it better to use as a ceiling eye.

25 Further purposes will appear in the specification and in the claims.

I have elected to illustrate two only, of the different forms of my invention, but have selected forms thereof that are practical and efficient in operation and which illustrate particularly well the principles involved.

Figure 1 is a vertical section through a ceiling and showing a desirable embodiment of my device to the ceiling, as a ceiling-eye.

30 Figure 2 is a bottom plan of Figure 1.

Figure 3 is a perspective view of the bracket of Figures 1 and 2.

35 Figure 4 is a vertical section through a wall and showing my device in the form of the bracket structure of Figures 1 and 2 and in use as a wall bracket.

Figure 5 is a perspective view similar to Figure 3 but showing a somewhat different form.

Like numerals refer to like parts in all figures.

40 Describing in illustration and not in limitation and referring to the drawing:

The illustrated embodiment of my invention is intended to comprise a useful and novel piece of hardware, easily manufactured, for use interchangeably as a wall-hook or as a ceiling-eye, in the one case to be supported by a single nail or screw toeing downwardly through outwardly spaced portions of the upper end of the bracket into the wall and in the other case supported by 45 two nails or two screws toeing longitudinally of

the bracket outwardly through downwardly spaced end portions of the bracket into the ceiling.

5 My bracket proper, as illustrated, comprises a metal strip 10 having preferably similar return bends 11 and 11' from the ends of an intermediate body 12, and with longitudinally offset perforations 13 and 14 toward each end of the bracket, respectively through the intermediate body 12 toward one end thereof and the adjacent return bend 11 or 11' and with the perforations 10 14 offset longitudinally of the bracket outwardly from the perforations 13.

When the bracket is to be used as an eye bracket, for example, as a ceiling-eye, it is placed with its hook side against the wall or ceiling 15 15 and fastened by two nails or two screws 16 each of which is positioned by the perforations 13 and 14 located toward one end of the bracket.

20 When the bracket is used as an eye-bracket the supporting nails or screws 16 toe away from one another into the wall or ceiling 15, thereby providing a more strong support and lessening the danger of fastening nails or screws splitting the supporting structure.

25 Preferably the bracket is contracted at the middle, at 17, to better accommodate any usual suspension element intended to be indicated conventionally at 18. As illustrated in Figures 1 to 3 this contraction at the middle of the bracket has been provided by oppositely recessing the 30 intermediate body at 17.

When the bracket is used as a hook bracket, for example, as a wall hook, it is placed with its intermediate body against the ceiling or wall and its hook side away from the ceiling or wall 19 35 to support any usual or suitable suspension element intended to be indicated conventionally at 18; the hook bracket being fastened to the wall by preferably a single nail or screw 16' positioned by the perforations 13 and 14 toward the upper end of the bracket and with the nail or screw 16' toeing downwardly along the bracket length.

40 In Figures 1 to 4 the bent ends 11 and 11' extend inwardly beyond the perforations 14 but as illustrated in Figure 5 this is not essential and I may optionally use shorter return bends 11' with merely end notches or recesses 14' to pass and laterally engage the supporting nail or screw or nails or screws 16.

45 The structure of Figure 5 is also easy and inexpensive to manufacture, optionally being made from perforate blanks cut successively from commercial perforate strip material—by cutting the perforate strip across the middle of every fourth 50

55

perforation—as along the lines 20—20 of Figure 5. The blanks are then formed with return bend ends, as in Figure 5 and finished in any suitable or desired manner, for example, optionally by 5 merely tumbling.

The application of the bracket of Figure 5 may be exactly as already described whether it is applied as an eye bracket or as a hook bracket.

In view of my invention and disclosure variations and modifications to meet individual whim or particular need will doubtless become evident to others skilled in the art, to obtain all or part of the benefits of my invention without copying the structure shown, and I, therefore, claim 10 all such in so far as they fall within the reasonable spirit and scope of my invention.

Having thus described my invention what I claim as new and desire to secure by Letters Patent is:

- 20 1. A bracket for attachment selectively to a wall or to a ceiling presenting to the wall or ceiling respectively reversed sides of the bracket and comprising a body portion and reversely turned ends extending generally toward each other and 25 spaced from the body portion, the body portion near the middle thereof being laterally-opposite recessed and near each end and each of the reversely turned portions being provided with guiding walls for a fastening device and the 30 guiding walls toward opposite ends of the body portion being nearer together than the guiding walls in the reversely turned ends whereby straight fastenings presented inwardly between and engaging the guiding walls of the body and 35 the guiding walls of the ends will diverge from the body portion toward the ends and converge from the ends toward the body portion.

2. A bracket for attachment selectively to a wall or to a ceiling presenting to the wall or ceiling respectively reversed sides of the bracket and comprising a body portion and reversely turned ends extending generally toward each other and 5 spaced from the body portion, the body portion near each end and each of the reversely turned portions being provided with guiding walls for a fastening device and the guiding walls of each reversely turned portion forming an end recess 10 and the guiding walls toward opposite ends of the body portion being nearer together than the guiding walls in the reversely turned ends whereby straight fastenings presented inwardly between and engaging the guiding walls of the body 15 and the guiding walls of the ends will diverge from the body portion toward the ends and converge from the ends toward the body portion.

3. A bracket for attachment selectively to a wall or to a ceiling presenting to the wall or ceiling respectively reversed sides of the bracket and comprising a body portion and reversely turned ends extending generally toward each other and spaced from the body portion, the body portion near each end and each of the reversely turned 20 portions being provided with guiding walls for a fastening device and the guiding walls toward opposite ends of the body portion being nearer together than the guiding walls in the reversely turned ends whereby straight fastenings presented inwardly between and engaging the guiding walls of the body 25 and the guiding walls of the ends will diverge from the body portion toward the ends and converge from the ends toward the body portion.

SAMUEL M. KASS.
